D. E. LAHEY.
RAILWAY TRACKAGE.
APPLICATION FILED JUNE 8, 1922.

1,435,011.

Patented Nov. 7, 1922.

UNITED STATES PATENT OFFICE.

DENNIS E. LAHEY, OF LOUISVILLE, KENTUCKY.

RAILWAY TRACKAGE.

Application filed June 8, 1922. Serial No. 566,842.

To all whom it may concern:

Be it known that I, DENNIS E. LAHEY, citizen of the United States, residing at Louisville, in the county of Jefferson and State of Kentucky, have invented certain new and useful Improvements in Railway Trackage, of which the following is a specification.

This invention relates to improvements in railway trackage, and more particularly to improved means for rendering a switch safe.

The primary object of the present invention is to provide improved filler blocks to be connected to the stock-rail and switch-point of a railway switch for the purpose of preventing a person's foot from being caught in the switch, and for the further purpose of preventing articles such as chains dragging from a train moving in either direction from being caught by the stock-rail or switch-point.

Another object of the invention is to provide filler blocks shaped to guide chains and the like hanging from a train through the switch or over the switch-point, so that there will be no likelihood of such an article being caught by the stock-rail or switch-point.

With the foregoing objects outlined and with other objects in view, which will appear as the description proceeds, the invention consists in the novel features hereinabove described in detail, illustrated in the accompanying drawing, and more particularly pointed out in the appended claims.

Referring to the drawing:

Figure 1 is a top plan view partly in section of a stock-rail and switch-point with the blocks arranged between the same.

Fig. 2 is a perspective view of the filler block which engages the stock-rail.

Fig. 3 is a perspective view of the filler block to be attached to the switch-point, said view being taken from a large end of said filler block and from the side which engages the switch-point.

Fig. 4 is a similar view of the switch-point filler block taken from the opposite side and end.

Fig. 5 is a vertical sectional view on a reduced scale taken on line 5—5 of Figure 1.

Fig. 6 is a transverse vertical sectional view taken on line 6—6 of Fig. 5.

Fig. 7 is a similar view taken on line 7—7 of Fig. 5. 55

Fig. 8 is a similar view taken on line 8—8 of Fig. 5.

In the drawing, 1 designates railway ties which support a stock-rail 2 and a switch-point 3. All of these parts are of ordinary construction and need not be modified to accommodate the improvements which I have devised.

As best seen in Fig. 2, the filler block to be applied to the stock-rail consists of a bar 4 of rectangular cross-section of the same dimensions throughout its length, with the exception of the end portions 5, which are beveled horizontally, as best shown in Fig. 1. These beveled ends facilitate the passage of articles dragging from a train along the filler block 4, and the ends 5 will not catch said articles and cause damage to the train or trackage. The block 4 is provided with a number of apertures 6 to receive 75 countersunk bolts 7 as shown in Figures 6, 7 and 8. These countersunk bolts are secured in place by means of nuts 8 arranged on the outer side of the web 9 of the rail 2. It will be noted that the inner face 10 of the 80 block aligns with the inner face 11 of the head of the rail, so that an unobstructed surface will be provided.

The switch-point filler block also consists of a substantially wedge-shaped bar 12 designed to be rigidly attached to the switch-point and to move with the latter. This filler block includes a base member 13 of substantially one-third the width of the head of the switch-point rail, and provided 85 at the large end of the block with a horizontally extending beveled portion 14, which is rather short in length. The opposite end of the base 13 is provided with a relatively long beveled portion 15 which is 90 adapted to engage the inner surface 10 of the filler block 4 when the switch-point is moved toward the rail 2.

Extending outwardly from the base 13 toward the stock-rail, is a wedge-shaped extension or guide 16, which is preferably integral with the base 13. At the position where the extension 16 merges into the base 13, the extension rises vertically as shown at 17 in order to form a longitudinally extending angular pocket 18 adapted to en-

gage the bottom and inner side of the head 19 of the switch-point rail 3.

It will be noted that the point 20 of the extension 16 is a vertical edge and that the 5 upper surface of the extension is gradually convexly curved downwardly and outwardly from said edge to the large end 21 of the extension. The large end of the extension is concavely curved transversely as shown 10 at 22, and it will be understood from an inspection of Figures 6, 7 and 8 that when the switch is closed and a train moves along the track in the right-hand direction, any part such as a chain hanging from a train 15 will engage the curved surface 22 and this curved surface will tend to guide the part along the groove 23 formed between the filler blocks. As the upper surface of the extension 16 is gradually inclined upwardly 20 as shown at 24 from the curved end 22 to the sharp edge 20, the part passing along the groove 23 will be guided upwardly and through the switch without causing damage to the tracks or train.

25 The filler block 16 is secured to the switch-point rail 3 by means of countersunk bolts 26 having nuts 27.

As preferably constructed, the switch-point filler 12 is beveled at either end as 30 shown at 14 and 15 and fits up on the side of the ball of the switch-point two-thirds of the way and then bevels one-fourth of an inch from there on to the bottom of the stock-rail, or where it connects with the 35 filler of the stock-rail it has a convex curvature in transverse direction, bearing from the large end 21 to the small end 20. The filler block 12 provides a substantial brace for the switch-point and absolutely prevents 40 a person's foot from being wedged between the switch-point and stock-rail and also prevents any article from dragging from a moving train in either direction from catching 45 between the stock-rail and switch-point.

50 From the foregoing it is believed that the construction, operation and arrangement of parts may be readily understood by those skilled in the art, and it is apparent that various changes may be made in the specific construction illustrated without departing from the spirit of the invention as expressed in the claims.

What I claim and desire to secure by Letters-Patent is:

1. The combination with a stock-rail and 55 a movable switch-point, of a substantially wedge-shaped filler block secured to the switch-point and having its upper surface curved downwardly and outwardly from the switch-point towards the base of the stock- 60 rail.

2. A combination as claimed in claim 1 in which the stock-rail is provided with a filler block to cooperate with the filler block of a switch-point, the filler block of the 65 stock-rail being provided with beveled ends.

3. A combination as claimed in claim 1 in which the stock-rail is provided with a filler block which cooperates with the filler block 70 of the switch-point, the filler block of the stock-rail being of substantially rectangular cross-section of the same dimensions throughout substantially its entire length, and being provided at its ends with inwardly beveled surfaces. 75

4. A combination as claimed in claim 1 in which the filler block is provided with a longitudinally extending angular recess adapted to engage the bottom and the inner side of the head of the switch-point. 80

5. A combination as claimed in claim 1 in which the filler block includes a base provided with a short inclined surface at one end and a relatively long inclined surface at the other end. 85

6. A combination as claimed in claim 1 in which the filler block includes a base provided at one end with a relatively short inclined surface and at its other end with a relatively long inclined surface, said base 90 being provided with a lateral wedge-shaped extension having its upper edge arranged above the upper edge of the base to form a longitudinally extending recess designed to engage the head of the switch-point, said 95 extension being provided at one end with a vertically arranged relatively sharp edge, and being provided at its opposite end with a transversely concaved surface, said extension having its upper surface inclined gradually downwardly and outwardly from its upper edge to its outer edge. 100

In testimony whereof I affix my signature.
DENNIS E. LAHEY. [L. s.]
